SOAP HOLDER

Joseph J. Nemeth, New York, N. Y.

Application March 1, 1945, Serial No. 580,349

11 Claims. (Cl. 45—28)

1

This invention relates to improvements to soap and has particular reference to an improved soap cake and holder or receptacle therefor.

Soap cakes as now manufactured and sold, including toilet soap as well as laundry and cleaning soap, are provided in generally square or rounded cakes of substantially homogeneous soap material. Such cakes, when wet, are slippery and difficult to handle and when placed in an ordinary holder or receptacle form a soap jelly in the bottom of the receptacle which wastes soap, renders it difficult to remove the soap from the receptacle and introduces an element of untidiness necessitating frequent cleaning of soap receptacles.

Means heretofore suggested for alleviating these conditions have consisted in embodying a cord, stem or hook in the soap cake so that the cake can be hung on some convenient projection when not in use. These proposed arrangements have not met with general approval for various reasons among which are probably the fact that a convenient hook or bracket is not provided in the usual bathroom, lavatory or kitchen and if the soap is hung up while wet there is an objectionable drip on the fixtures or floor.

Present soap cakes also are extremely wasteful in that there is always a residual piece of soap that becomes thin enough to break or crumble before it can be used up. The soap in such a residual piece is not only wasted but the small pieces of soap tend to lodge in drains and frequently lead to unsatisfactory functioning of the plumbing. It is not known that any special remedy for this condition has heretofore been proposed.

Also, it is a matter of common knowledge that the brand name, trademark, manufacturer's name and/or advertising matter are usually imprinted into the surface of the soap cake and that these impressions are lost when the soap has been used a very few times.

It is accordingly among the objects of the present invention to provide an improved soap cake which provides a firm and non-slippery grip for the user even when the soap cake is wet.

A further object of the invention resides in the provision of an improved soap cake and holder therefor so constructed that the soap cake is suspended out of contact with the holder, thus precluding the formation of soap jelly in the holder and consequent wastage of soap.

A further object resides in the provision of an improved soap cake and holder therefor so constructed that the soap may be easily and quickly inserted in the holder or receptacle and removed

2

therefrom and yet will remain firmly in place in the receptacle when not in use.

An additional object resides in the provision of an improved soap cake having a reinforcing core member extending therethrough so that all of the soap in the cake can be used and there will be no residual unusable pieces to be wasted or to interfere with proper functioning of drainage plumbing.

Another object resides in the provision of an improved soap cake having embedded therein a member of relatively rigid insoluble material to which advertising or other matter may be applied so that it will remain in evidence until the soap cake is entirely used up.

Yet another object resides in the provision of an improved soap cake and holder therefor so constructed that the soap cake is suspended out of contact with the holder and a cover which, when applied to the holder, is definitely spaced from the soap cake.

Other objects and advantages of the invention will become apparent as the description proceeds in connection with the accompanying drawings and from the appended claims.

In the drawings:

Figure 1 is an elevational view of an improved soap holder or receptacle with a cover applied thereto;

Figure 2 is a plan view of the soap holder shown in Figure 1 with the cover removed and a soap cake in place in the holder;

Figure 3 is a plan view of the interior of the cover shown in Figure 1;

Figure 4 is a vertical sectional view on the line 4—4 of Figure 2 with the cover in place;

Figure 5 is a transverse vertical sectional view on the line 5—5 of Figure 1;

Figure 6 is a transverse vertical sectional view on the line 6—6 of Figure 1; and

Figure 7 is a perspective view of a core member which is embedded in the body of soap material comprising the improved soap cake.

With continued reference to the drawings, and particularly to Figures 1, 2 and 3, the numeral 10 generally indicates the soap holder or receptacle and the numeral 12 generally indicates a cover for the soap holder. It is to be understood, however, that the invention is in no way limited to the provision of a cover for the improved soap holder, but that the holder may be installed as a permanent fixture in a bathroom, lavatory or kitchen or other desirable location and no cover provided. The cover provides a convenient portable receptacle for the improved soap cake and

particularly one which may be conveniently packed in luggage for traveling or to provide an individual soap container where a number of persons are required to use the same lavatory facilities.

The soap holder may be conveniently formed of some resinous plastic material or of ceramic material or metal as may be desired and comprises a hollow body having an interior cavity 14 somewhat larger than a new cake of soap. At each end of the cavity 14 there is provided an integral seat, as indicated at 16 and 18. Each seat has an upper edge substantially parallel to the bottom wall of the holder and spaced above the bottom wall a distance at least as great as one-half the thickness of a soap cake and preferably a somewhat greater distance to provide an adequate space between the bottom surface of the soap cake and the bottom of the holder so that water, dripping from the soap cake or accidentally splashed into the holder, will not come in contact with the soap. Each of these seats may conveniently comprise a web portion 20, which is in effect a continuation of the bottom wall of the holder, and a pair of reinforcing flange portions 22 and 24 which not only reinforce the web portion but provide abutments at each end of the seat for a purpose which will presently appear. The soap receiving concavity of the holder may be surrounded by a lateral web portion 26 having peripherally thereof a flange 28 along the free edge of which may be provided suitable tabs or legs as indicated at 30 and 32.

The improved soap cake comprises an elongated core member generally indicated at 34, one form of which is particularly illustrated in Figure 7. This core member may be formed of any suitable relatively rigid and insoluble material such as wood, plastic resin, treated paper, etc. The core has an intermediate portion 36 which is preferably elliptical in cross section, as is particularly illustrated in Figures 5 and 6, and the cross sectional dimensions of the intermediate portion of the core preferably approximate the dimensions of the residual piece of the soap cake which is unusable because of its tendency to break or crumble. At each end of the intermediate portion 36, the core member may be provided with a grooved or reduced portion, as indicated at 38 and 40, and beyond these reduced portions, may be provided with transversely extending end or grip portions, as indicated at 42 and 44. Preferably the outer end surfaces of the grip portions are serrated, grooved or roughened as indicated at 46 to provide an improved grip for the hand when handling the soap cake, especially when wet. These end portions 42 and 44 may carry such advertising or instructive matter as may be desired and since the material thereof is relatively insoluble, such material will remain in evidence for the entire life of the soap cake. The edges and corners of the end portions 42 and 44 are rounded as indicated by the shading in Fig. 7 to prevent injury to the user of a bar of soap containing the core member 34. Surrounding the core member 34 there is a body of soap material 50 which has the core substantially at its center and may be of the size and general shape of a cake of soap of any selected brand now on the market. If desired, the intermediate portion of the core member may be perforated or have its surface roughened so that the soap material will adhere thereto until completely used up.

In the particular form illustrated, the body of soap material has a main portion 52 of generally

rectangular cross section and a ridge portion along each edge, as indicated at 54 and 56. As particularly shown in Figure 2, these ridge portions 54 and 56 are brought around the ends of the main body 52 and form extensions, one of which is indicated at 58, at the ends of the body of soap material, the outer surfaces of which extensions lie substantially in a common plane with the corresponding end surface of the grip portion of the core member. By making the end portions of the soap body at each side of the projecting or exposed end portion of the core member flush with the end of the core member, the wrapping and packaging of the soap is greatly facilitated and the wrappings will not be broken by the projecting core ends.

While the above described form of soap cake has been found to be advantageous, the invention is not necessarily limited to any particular form, it being necessary only for the purpose of accomplishing the invention that the ends of the core member be exposed, one at each end of the soap cake.

As is particularly shown in Figures 2 and 4, when the soap cake is placed in the holder or receptacle, the upper surfaces of the seats 16 and 18 fit into the notches or reductions provided between the grip portions 44 and 46 and the intermediate portion 36 of the core member so that the soap cake is definitely located in a longitudinal direction relative to the holder. At the same time, the ends of the corresponding flange portions 22 and 24 form abutments for the corresponding edges of the core member to locate the soap cake in the holder against lateral displacement. The soap cake is thus suspended, as is clearly indicated in Figures 4 and 5, entirely out of contact with any portion of the holder and will remain in a dry and solid condition and will not form soap jelly in the holder.

The cover member 12 is generally dome-shaped and has a terminal flange portion 60 which closely fits the flange portion 28 of the holder 10. Internally the cover member is preferably provided with a pair of webs as indicated at 62 and 64, the lower edges of which rest upon the upper surfaces of the corresponding core notches 38 and 40 and hold the cover member spaced from the surface of the soap cake as is clearly illustrated in Figure 4 and retain the core member on the seats of the holder so that the cake cannot become loose in the holder. Externally the flange portion 60 of the cover member is surrounded by a bead 66 and the holder flange 28 is surrounded by an integral external bead 68. These beads are spaced apart and provide convenient grips to facilitate removal of the cover from the holder 10.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and language of equivalency of the claims are therefore intended to be embraced therein.

I claim:

1. In the combination of a soap cake and a holder therefor, a rigid core for said cake having exposed end portions; means in said holder adapted to support said soap cake by the end portions of said core; and a cover for said holder

having means adapted to contact the end portions of said core to space said cover from said soap cake.

2. A soap holder comprising a receptacle having a seat therein spaced inwardly from each end thereof; and a cover engageable with said receptacle and having a depending projection therein spaced from each end thereof and disposed in vertical registration with each seat.

3. A soap holder as defined in claim 2 wherein said receptacle and said cover have interfitting flange portions and each flange is provided with a surrounding bead, said beads being spaced to provide convenient means for removing said cover from said receptacle.

4. In combination, a soap cake; an elongated core extending through said soap cake with its ends projecting beyond said soap cake, each of the projecting ends of said elongated core being provided with a transverse notch; and a holder for said soap cake including a body portion, and a pair of spaced seats on said body portion engaged with the notched ends of said elongated core and arranged to support said soap cake in spaced relation to said body.

5. A soap cake, comprising: a body of soap material; an elongated core extending through said body of soap material with its ends projecting beyond the ends of said body of soap material, each of the projecting ends of said core being provided with a transverse notch adapted to be engaged with a seat on a soap holder.

6. In combination, a soap cake; an elongated horizontal core extending through said soap cake with its ends projecting beyond said soap cake, each of the projecting ends of said core being provided with a transverse notch on the upper and lower sides thereof; a holder for said soap cake including a body portion and a pair of spaced seats projecting upwardly from said body portion and engaged with the notches formed in the lower side of said core; and a cover for said soap cake holder including downwardly projecting webs engaged with the notches in the upper side of said core.

7. In combination, a soap cake; an elongated core extending centrally through said soap cake with its ends projecting beyond said soap cake; and a holder for said soap cake including a body portion, a pair of transverse seats projecting upwardly from said body portion engaged with the ends of said elongated core and supporting said soap cake in spaced relation to said body, and projections at each end of said transverse seats arranged to limit transverse movement of said elongated core relative to said seats.

8. In combination, a soap cake; a core extending through said soap cake with its ends projecting beyond said soap cake; a holder for said soap cake; a cover for said holder; and means extend-

ing from said holder and cover, respectively, engageable with the projecting ends of said core arranged to maintain said soap cake out of contact with the walls of said holder and cover.

5 9. In combination, a soap cake; a core in said soap cake; a holder for said soap cake; a cover for said holder; and means extending from said holder and cover, respectively, engaging with said core and arranged to maintain said soap cake out of contact with the walls of said holder and cover.

10 10. In combination, a soap cake; a core in said soap cake; a holder for said soap cake; means on said holder engaging a surface on said core 15 to support said soap cake out of contact with said holder; a cover for said holder; and means on said cover engaging another surface on said core to maintain said cover out of contact with said soap cake.

15 11. In combination, a soap cake; a core in said soap cake; a holder for said soap cake; means extending upwardly from said holder and supporting said soap cake out of contact with said holder; a cover for said holder; and means

20 25 depending from said cover and engaging said core to maintain said cover out of contact with said soap cake, said holder and cover having surfaces in frictional engagement for retaining said cover in assembled relation with said holder and for firmly holding said soap cake in fixed 30 position within said holder and cover when not in use.
